A. L. CHAMPION

WEATHERPROOF WINDOW

Filed Aug. 26, 1926

FIG. 1.

UNITED STATES PATENT OFFICE.

ABRAHAM L. CHAMPION, OF BOSTON, MASSACHUSETTS.

WEATHERPROOF WINDOW.

Application filed August 26, 1926. Serial No. 131,741.

This invention relates to a window constructed to prevent the entrance of wind, dust and rain.

A primary object of the invention is to construct a window with sealing means at the meeting points of the sash and at the junction of the sash with the side rails of the frame.

With these and other objects in view, the invention consists in certain novel features of construction and combination and arrangement of parts which will be more fully hereinafter described and pointed out in the claims.

15 In the accompanying drawings:—

Fig. 1 represents a perspective view partly in section of an upper and lower window sash with this improvement shown applied.

Fig. 2 is a perspective view of the top of 20 the lower sash.

Fig. 3 is a similar view of the lower portion of the upper sash.

Fig. 4 is a perspective view taken from the bottom of the lower rail of the upper sash.

25 Fig. 5 is a transverse section taken on the line 5—5 of Fig. 1.

Similar reference characters indicate corresponding parts in all the figures.

This invention contemplates in the construction of such a protector for windows of the sliding sash type, the provision of a cap plate 10 to be located on the upper face of the top rail of the lower sash to overlap the joint between the sash rendering the window 30 windproof when closed; another cap plate 20 on the lower face of the bottom rail of the upper sash which underlaps the lower face of the top rail of the lower sash and carries a strip 21 fitting in the joint between the 35 meeting rails and providing what may be termed a reinforcing shoe for breaking the air.

In carrying this invention into effect, it is proposed to mount it on a sliding sash window, the frame of which is shown at 1 and includes side rails 2 equipped with the usual stops 3. Slidable in frame 1 is the lower sash 4 which includes stiles 5 and a top rail 6 on which the protector or cap plate 10 is mounted.

The upper sash also slides in frame 1 and includes stiles 8 and a bottom rail 9 on the lower face of which rail the air break reinforcing shoe 20 is secured.

50 In that connection, it is to be noted that one of the distinctive features of this in-

vention resides in so mounting the protector or shoe 20 that it may be speedily removed, and applied and when applied is securely held and yet quickly and easily released.

The cap plate 10 shown in Figs. 1, 2 and 5 is preferably made flat and of a length corresponding to the length of the top rail 6 of the sash 4 or slightly longer than said rail, 60 the ends of said plate being cut out as shown at 11 to fit the ribs on the inner faces of the side rails 2 of the window frame. The inner corners of this plate are notched as shown at 12 to fit around the stiles 8 of the upper 70 sash. This plate 10 projects at its rear edge beyond the rear face of the upper rail 6 of the sash 4 to form an overlapping lip 13 designed to fit between the stiles 8 of sash 7 and to overlap the lower rail 9 thereof to 75 protect the joint between the meeting rails of the two sashes. Midway the rear edge of the lip 13 is formed a notch 14 designed to slidably engage the center rib or partition 8^a of the upper sash. This plate 10 may be 80 constructed of any suitable metal or other materials and has positioned between it and the rail 6 to which it is secured a layer of felt 15 or other suitable material to insure an air and dustproof connection between the meeting rails of the sash. The longitudinal edges of the plate 10 is turned down over the 85 edges of said layer of felt.

The protecting shoe or reinforcement 20 which is detachably mounted on the lower 90 face of the lower rail 9 of the upper sash 7 is made T-shape in cross section as shown clearly in Fig. 5, being in the form of a plate folded midway the width thereof to provide a rib-like member 21 designed to be 95 inserted between the meeting faces of the rails 6 and 9 of the lower and upper sash. This plate 20 has a forwardly projecting lip 22 designed to overlie the lower face of the rail 6 of sash 4, while the body portion of 100 the plate is provided with a plurality of longitudinally disposed slots 23 for the passage therethrough of screw-eyes 24 to secure the plate to the lower face of rail 9 as shown clearly in Figs. 4 and 5. These 105 screw-eyes are first placed in the rails and the plate is applied thereto by turning the eyes so that the slots 23 will slip over said eyes and when the plate is properly adjusted, these screw-eyes are turned so as to be arranged transversely of the slots and thus 110 securely hold the plate in position and yet

permit it to be readily removed when desired.

The projecting lip 22 of the plate 20 is provided midway its length with a notch 22^a designed to slidably engage the intermediate rib 5^a of the lower sash 4.

It will thus be seen that when the cap plates 10 and 20 are applied to the rails 6 and 9 as shown in Figs. 1 to 5 and the window sash closed, all air and dust will be effectively excluded at this point.

Without further description, it is thought that the features and advantages of the invention will be readily apparent to those skilled in the art, and it will of course be understood that changes in the form, proportion and minor details of construction may be resorted to without departing from the spirit and scope of the claimed invention.

I claim:

1. The combination with sliding upper and lower window sashes having meeting rails, of a cap plate secured to the top face 23 of the upper rail of the lower sash and extending over the joint between said upper rail of the lower sash and the lower rail of the upper sash, and a layer of felt between the cap plate and the upper faces of said upper and lower rails, said cap plate having its edges turned down over the edges of said layer of felt and into engagement with said upper faces of the rails.

2. The combination with sliding upper and lower window sashes having meeting rails, of a cap plate secured to the top face of the upper rail of the lower sash and extending over the joint between said upper

rail of the lower sash and the lower rail of the upper sash, a layer of felt between 40 the cap plate and the upper faces of said upper and lower rails, said cap plate having its edges turned down over the edges of said layer of felt and into engagement with 45 said upper faces of the rails, another cap plate secured to the lower face of the lower rail of the upper sash having a forwardly projecting flange to lap the joint between the rails on the lower face thereof and having means arranged between the rails to 50 form an air-tight joint.

3. The combination with sliding upper and lower window sashes having meeting rails of a single metal plate bent longitudinally upon itself midway between the side 55 edges to form two parallel, upwardly extending flanges, one of which is adapted for tight engagement with the inner side of the lower rail of the top sash and the other of which is adapted for tight engagement with the inner side of the upper rail of the lower sash, integral oppositely projecting horizontal flanges on the lower edges of each of said upwardly extending parallel flanges, one of said horizontal flanges engaging the 60 lower side of the lower rail of the upper sash and the other horizontal flange engaging the lower side of the upper rail of the lower sash and means for detachably securing the first mentioned horizontal flange to 65 the lower side of the lower rail of the top sash.

In testimony whereof I have hereunto affixed my signature.

ABRAHAM L. CHAMPION.
